FRANCE, ASSIGNEES, BY MESNE ASSIGNMENTS, TO THE R. U. V. COMPANY, INC., A
CORPORATION OF NEW YORK.

STERILIZATION OF LIQUIDS.

1,124,737.

Specification of Letters Patent. Patented Jan. 12, 1915.

Original application filed June 7, 1910, Serial No. 565,610. Divided and this application filed December 24, 1912. Serial No. 738,423.

To all whom it may concern:

Be it known that we, VICTOR HENRI and ANDRÉ HELBRONNER, citizens of the Republic of France, and MAX VON RECKLINGHAUSEN, a subject of the Emperor of Germany, residing at Paris, France, have invented new and useful Improvements in the Sterilization of Liquids, of which the following is a specification.

10 In the specification filed with our application for Letters Patent on 26th February 1910 Serial No. 546252, we have described a process for the sterilization of liquids by means of the action of ultra-violet rays, in which process, where the liquid to be sterilized possesses a high degree of opacity to the rays, we arrange that it shall be caused to flow in a thin film in order that all its particles may be exposed to the desired influence.

20 The present invention relates to an improvement on the process above mentioned and in accordance therewith thin films of the liquid are produced by means of a force 25 greater than gravity as we have found that many liquids, milk for example, do not under the action of gravity alone form a sufficiently thin film to enable the liquid to be sterilized quickly and thoroughly.

30 Apparatus for carrying out the process according to the present invention is described in the specification filed with our application for United States patent on the 7th June 1910, Serial No. 565610, of which 35 the present application is a division.

40 In our improved method the force which we employ is that of adhesion and we arrange the apparatus in such a manner that this force shall be opposed by gravity acting upon a film which is drawn out by a continuously moving surface upon which the liquid to be sterilized, milk for example, is delivered. By causing the surface to travel away from the liquid in an upward 45 direction we insure that the force forming the thin film shall be greater than gravity which naturally tends to draw the film downward and we thereby obtain an extreme attenuation which enables all the particles of the liquid to be exposed to the 50 action of the ultra-violet rays during a very short period of time.

In order that the nature of our invention

may be clearly understood we will now describe the same by the aid of the accompanying drawing which is a perspective view somewhat diagrammatic, illustrating an apparatus by means of which it may be carried into practical effect.

55 A hollow cylinder 1 is provided supported on a bearing in which it may be rotated and having approximately in the axis thereof of a source of ultra-violet rays indicated at 2 as being a mercury vapor lamp with a quartz container of a well known type. The 60 liquid to be sterilized, milk for example, is delivered from a pipe 3 through holes or jets 4 therein on to the inner periphery of the cylinder 1 near the bottom thereof. As the cylinder is rotated in the direction of 65 the arrow the liquid is drawn out into a film by reason of the adhesion its thickness being regulated by means of a V-shaped baffle plate or scraper 5 which also 70 causes the surplus liquid to be moved toward the ends of the cylinder. As the cylinder is continuously rotated the film is carried upward on the left of the figure in opposition to the force of gravity acting thereon and is subjected to the ultra-violet rays 75 emanating from the source 2. The film is scraped off the cylinder by the stationary plate 6 which collects the liquid and delivers it through the pipe 7 leading to the receptacle for sterilized liquid.

80 We claim as our invention:

1. The method of sterilizing liquids, which consists in delivering the liquid to a moving surface, forming the liquid so delivered into a thin film by means only of the adhesive 85 force between said liquid and said moving surface, and exposing the same to the action of ultra-violet rays.

2. The method of sterilizing liquids, which consists in delivering the liquid to a continuously rotating surface, forming the liquid so delivered into a thin film by means only of the adhesive force between said liquid and said rotating surface, exposing the film of liquid thereon to the action of 90 ultra-violet rays, and collecting the sterilized liquid from said surface by suitable means.

3. The method of sterilizing liquids, which consists in delivering the liquid to the interior surface of a cylindrical body slowly 95

and continuously rotating around a horizontal axis, forming the liquid so delivered into a thin film by means only of the adhesive force between said liquid and said rotating surface, and exposing the film of liquid thereon to the action of ultra-violet rays, and collecting the sterilized liquid from said surface by suitable means.

In testimony whereof we have hereunto

subscribed our names this fifth day of December 1912.

VICTOR HENRI.

ANDRÉ HELBRONNER.

MAX VON RECKLINGHAUSEN.
